UNITED STATES PATENT OFFICE.

OTTO GERMER AND CHARLES G. MOULTON, OF ERIE, PENNSYLVANIA,
ASSIGNORS TO BLACK & GERMER, OF SAME PLACE.

DESIGN FOR A HEATING-STOVE.

SPECIFICATION forming part of Design No. 16,789, dated July 13, 1886.

Application filed May 7, 1886. Serial No. 201,454. Term of patent 7 years.

To all whom it may concern:

Be it known that we, OTTO GERMER and CHARLES G. MOULTON, citizens of the United States, residing in the city of Erie, in the county of Erie and State of Pennsylvania, have invented a certain new and original Design for Heating-Stoves; and we do hereby declare the following to be a full, clear, and exact description of the invention, such as to will enable others skilled in the art to which it appertains to make and use the same, reference being had to the accompanying drawing, and to the letters of reference marked thereon, forming part of this specification.

Our design relates to the form and ornamentation of heating-stoves; and it consists in the features hereinafter set forth and described.

The design is illustrated in the accompanying engraving, showing a perspective view of a heating-stove embodying the same.

In its general shape the stove is rectangular, with a swell front terminating in an ornamental dome-shaped cap just above the overhanging molding of the top of the stove. In its general shape the base A is rectangular, and curves from near its junction with the upright portion of the stove downward at B to the curtain C, which is ornamented with a running foliated vine, D, springing from the lower part of the feet E at the corners and meeting near the centers of the sides and ends of the curtain C. The curved part B of the base is divided into front, end, and corner panels, the front panel being occupied by the name-plate and the corner panel, F, ornamented with foliate and scroll work. The corners I of the first section, II, above the base, forming the ash-pan chamber, form pilasters J on the front and ends of the stove, their ornamentation consisting of the semicircular corner-posts J', with spiral beads K on each side thereof. The outcurved front of the ash-pan chamber is formed of a single door, L, covered with open foliate and volute scroll-work N. The ends of the ash-pit are also ornamented with foliate and scroll work O. The ends are also provided with ornamental brackets P. The ash-pan section II is surmounted by a projecting ogee band-mold cornice, R. Upon this cornice the next section, S, surrounding the fire-chamber and fire-pot, rests. The pilasters T of this section are substantially the same design as those of the ash-pan section II. The ends of this section consist of single doors U, having therein six rectangular openings for mica windows, the upper of which are vertically narrower than the lower ones, the styles of these doors being ornamented with raised filigree, rosette, and scroll work. The front of this section consists of the double doors V, curved outwardly to conform to the contour of the front, these doors V having each four openings, the lower of which are vertically the largest, and having their styles ornamented with filigree, rosette, and scroll work. This section S is also surmounted by a projecting beaded band-mold cornice, W. Upon this cornice W the next section, 1, surrounding the combustion-chamber, rests. The pilasters 2 of this section consist of semicircular corner-posts 3, with serrated borders on each side thereof. The ends of this section consist of single doors 4, having therein nine rectangular openings for mica windows, the upper row of which is vertically narrower than the others, the styles of these doors being ornamented the same as those in the section S. The front of this section consists of double doors 5, curved outwardly to conform to the contour of the front, hinged at the corners of the stove, and closing together at the center of the front. These doors 5 have each six openings for mica windows, the upper row being vertically narrower than the others, and having their styles ornamented the same as those in the front of the section S. The section 1 is surmounted by a fillet, 6, above which is a broad band, 7, which at the corners of the stove forms the pilaster-caps 8, these caps 8 being ornamented with foliate work, while across the front the band 7 is ornamented with foliate work and tile medallions and rosettes, and across the ends with foliate work and rosettes. The section 9 extends from the top of the band 7 to the facia 10 of the overhanging cornice 11 of the stove-top. The center of the front of section 9 consists of a central dome-shaped panel, 12, ornamented with an antique group in bas-relief. The ends of section 9 consist of a central arched panel, 13, ornamented with antique figures in bas-relief. Above the panels

ML

12 and 13 is a narrow band of ogee molding, 14, which is broken around the corners of the stove between the panels 12 and 13, so as to form a continuous molding. At each of the 5 four corners of section 9 are human faces 15, surrounded with foliate and scroll work 16, of conventional form, filling the space between the molding 14 and the facia 10. The 10 facia 10 is ornamented with foliate work and rosettes. The central portion of the stove-top is an oval dome, 17, having the top thereof cut off at 18, so as to form a flat surface to support an ornamental figure, 19. The outside of the dome 17 is ornamented with scroll-work 15 and serrated and plain bands. From the base 15 of the dome 17 the stove top 21 curves gradually downward to a point near the edge of the overhanging cornice 11, and is ornamented with volute scroll-work and an ornamental serrated band below the scroll-work, the edge of 20 the top terminating in a beveled band, 20.

Having thus fully described our design, what we claim as new, and desire to secure by Letters Patent of the United States, is—

- 25 1. In a design for a heating-stove, the base A, consisting of the curved portion B, having side and end panels, F, ornamented substantially as shown and described, and the curtain C, having the foliate vine-shaped ornaments D, substantially as shown and described.
2. In a design for a heating-stove, the section II, consisting of the pilasters J, the ornamental open foliate and volute scroll-work N on the front, foliate and foliate scroll-work O on the ends of the section II, the brackets P, the fender-bars Q, and ornamental ogee cornice R, substantially as shown and described.
3. In a design for a heating-stove, the section S, consisting of the pilasters T, the end doors, U, and the double front doors, V, having their styles ornamented with raised foliate, scroll, and rosette work, and the ornamental beaded cornice W, substantially as shown and described.
4. In a design for a heating-stove, the section 1, consisting of the pilasters 2, the doors 4 on the ends, and the double front doors, 5, having their styles ornamented with raised foliate, scroll, and rosette work, and the fillet 6, and ornamental band 7, and the pilaster-caps 8, substantially as shown and described.
5. In a design for a heating-stove, the section 9, consisting of the dome-shaped front panel, 12, ornamented with an antique group in bas-relief, and the arched end panels, 13, ornamented with antique figures in bas-relief, the ogee molding 14, and the corner face ornaments 15, foliate scroll-work 16, and ornamental facia 10, substantially as shown and 60 described.

6. In a design for a heating-stove, the top section thereof, consisting of the shell and scroll and band ornamented oval dome 17, surmounted by an ornamental figure, 19, the downward-curved part 21, forming the stove-top, and cornice 11, ornamented with volute scroll-work and serrated bands, and the plain beveled band 20, substantially as shown and described.

7. The design for a heating-stove, consisting of the rectangular base A, ornamented substantially as shown, the ash-pan section II and its cornice R, substantially as shown, the sections S and 1, having the beaded cornice between them, all substantially as shown, the ornamental band 7 and pilaster-caps 8, substantially as shown, the section 9, with its ornamental dome front and arched end panels, ogee molding, corner ornaments 15 and 16, and ornamental facia 10, substantially as shown, and the section consisting of the ornamental dome 17, downward-curved and ornamental top 21, and the cornice 11, substantially as shown and set forth.

8. In a design for a heating-stove, the rectangular base A, consisting of the downward-curved portion B, having the ornamental corner panels, F, and a foliated vine-ornamented curtain, C; the ash-pan section II, having the pilasters J, the open foliate and volute scroll-work front N, and ends ornamented with foliate and scroll work O, and the brackets P, fenders Q, and the ogee cornice R; the sections S and 1, separated by the beaded cornice W, having pilasters T and 2, and end doors, U and 4, and double front doors, V and 5, having their styles ornamented with raised filigree, scroll, and rosette work, the fillet 6, band 7, and pilaster-caps 8; the section 9, consisting of the dome-shaped front panel, 12, ornamented with an antique group in bas-relief, the arched end panels, 13, ornamented with an antique figure in bas-relief, the ogee molding 14, the corner face ornaments 15, and foliated scroll-work 16, and ornamental facia 10; and the top section, consisting of the downward-curved part 21, forming the stove-top, and cornice 11, ornamented with volute scroll-work, serrated bands, and the plain band 20, surrounded by the shell and band 105 ornamented oval dome 17, substantially as shown and set forth.

In testimony whereof we affix our signature in presence of two witnesses.

OTTO GERMER,
CHARLES G. MOULTON.
